UNITED STATES PATENT OFFICE

155,882

DESIGN FOR A BELL

Max Feintuch, Brooklyn, and Benjamin F. Jay,
New York, N. Y.

Application June 9, 1948, Serial No. 146,854

Term of patent 7 years

(Cl. D56—1)

To all whom it may concern:

Be it known that we, Max Feintuch, a citizen of the United States, residing in Brooklyn, in the county of Kings, State of New York, and Benjamin F. Jay, a citizen of the United States, residing in New York city, county and State of New York, have invented a new, original, and ornamental Design for Bell, of which the following is a specification, reference being had to the accompanying drawing, forming a part thereof, in which:

Fig. 1 is a front elevational view of a bell, showing our new design;

Fig. 2 is a side elevational view thereof, and

Fig. 3 is a bottom plan view thereof.

We claim:

The ornamental design for a bell, as shown.

MAX FEINTUCH.
BENJAMIN F. JAY.
